UNITED STATES PATENT OFFICE.

MARCUS B. MATSON, OF NEW YORK, N. Y.

AUTOMATIC SAFETY APPLIANCE FOR GAS BURNERS.

Application filed October 30, 1925. Serial No. 65,867.

This invention relates to a thermo-electrically controlled gas cut-off valve which controls the flow of gas to one or more gas burners or fixtures and is an improvement 5 over the subject matter of my pending application Serial No. 41,864, series of 1925, filed July 6th, 1925, in which the cut-off valve control is achieved thermo-mechanically. The control described in my pending 10 application is desirable where the control of gas for but a single burner is contemplated. My present invention is desirable and practical when the control of gas to a battery of burners or gas fixtures is contemplated. 15 Both inventions render it impossible for unignited gas to flow from a burner.

The principal object of this invention is the prevention of accidental asphyxiations and the deterrence of suicide from gas 20 appliances.

Another object of my invention is to provide an extremely simple, inexpensive, and positively acting automatic appliance for stopping the flow of fuel to a fuel burning 25 fixture, or the like, whenever the fixture cock is set to permit the flow of fuel therethrough and the fuel is not burning at the fixture.

A further object of my invention is to 30 provide an appliance of the character described which operates on electric current and requires only a single circuit and a minimum number of circuit making and breaking devices or other movable parts.

A further object is the provision of a cut-off valve, the operation of which may be retarded to allow the operator sufficient time to light the burner after turning on the cock, before said cut-off valve closes completely.

This timing is accomplished by varying the 40 electrical resistance of the heating element surrounding the valve and by regulating the ventilation of the protective housing that encloses both the heating element and the valve.

A still further object of my invention lies in the fact that the device is completely automatic; it functions only in an emergency when unignited gas is flowing from a 50 burner. No change whatever from customary methods is necessitated in the operation of the fixtures. The device is not easily disordered and is fool-proof. Current consumption is negligible and cost of manufacture is small.

In accordance with my invention, I provide in the fuel supply pipe to a fuel burning fixture, or the like, an electric safety shut-off valve which is controlled by two electric switches, one of which is thermally controlled by flame conditions at the fixture and the other of which is controlled by the adjustment of the cock of the fixture. I prefer to place these switches in series in the circuit which operates the shut-off valve, thus requiring only a single circuit for the safety appliance. The thermal switch at the fixture is preferably of the "snap action" type and its electrical contacts are shielded from the heat of the flame and from dust, 60 dirt, grease, and the like, which might cause improper contact at the terminals and otherwise interfere with the positive operation of the switch. 65

As illustrative of an apparatus for carrying my present invention into effect, reference is made to the accompanying drawing, in which:

Fig. 1 is a diagrammatic view of the invention adapted to a single gas burner of 70 the range type. It is evident, however, from the construction shown, that the device may be extended to cover a plurality of burners or fixtures.

Fig. 2 is a detailed view of the gas cut-off 75 valve.

Fig. 3 is a cross-sectional view on the line 3-3 of Figure 2.

Fig. 4 is a diagrammatic view of another type of thermo-electric contact than that included in Figure 1. 80

In Figure 1 of the drawing there is shown a burner 1 with air control 7 and gas cock 10 connected to supply manifold 13. Manifold 13 may be extended to supply gas to a 90 plurality of other burners. Installed at a point on the supply main before the gas is diverted through cocks to any of the burners or fixtures is a gas cut-off valve, comprising, generally a container 16 filled with a suitable 95 thermal medium 29^a (usually a hydro-carbon oil), a piece of corrugated expanding and contracting tubing 30 made tight to cap 21, rod 23 and valve gate 24 by soldered connections 22. Also provided is filling plug 17, 100 valve structure 15 with valve seat 25 and heating element 14 surrounding container 16 and insulated therefrom by strips 20. Protective housings 27 and 28 which are secured 105 by means 31 to container 16 have adjustable 110

ports to vent excess heat, and, enclose heating element 14 and thermal container 16. Supply main 26 and supply manifold 13 are attached as shown to the cut-off valve.

5 Installed in the main line 19 is a switch 18 to be used only in the event of a part of the device failing to function.

To manifold 13 is fastened clamp 12 which contains insulated contact strip 8. To the 10 bottom part of the core of gas cock 10 is fastened support 11 in such a manner that it will move angularly the same as gas cock handle 29 when same is manually actuated. Secured to support 11 is insulated contact 15 strip 9.

Exposed to the heat from burner 1 is thermal disc 2 embodied in structure 6 which is clamped in proper position, in relation to the heat, to burner 1. To thermal disc 2 by 20 means of rod 3, is fastened contact disc 5 with adjustment means 30. Fastened to and insulated from structure 6 are contacts 4.

Thermal disc 2 is designed to "flip" from 25 concave to convex position when a temperature of approximately 200° F. is exceeded and conversely to "flip" back to concave position when the temperature falls below this point. When the burner is not lighted and the temperature is below 200° F. the disc 2 is in concave position and the circuit is completed at this point through contact disc 5 and contact points 4. When the burner is lighted and the temperature surrounding the disc 2, even at a very low flame, exceeds 200° 30 F. The disc is in convex position and the circuit is broken by the automatic removal of contact disc 5 from contact points 4.

Figure 4 discloses another type of thermo-electric contact at the burner. In the 40 figure, strips 33 and 34 are metals possessing different coefficients of expansion fastened together by means 35 and made rigid to the burner at the base 36. Piece 32 is secured to but insulated from (except at point of 45 contact 37) strips 33 and 34. When heat is applied to this portion of the apparatus the strips 33 and 34 will expand away from piece 32 breaking contact, at point of contact 37, in the circuit. Additionally, there 50 are numerous other ways of accomplishing this thermo-electrical contact not shown on the drawing nor described in this specification, the two methods shown merely being deemed best suited for the device.

55 When gas cock 10 is in off position as shown in Fig. 1, the circuit at this point is broken. When, however, it is turned to any part of on position, the circuit is completed through contact strips 8 and 9.

60 In operation the device functions as follows:

In the ordinary manner the gas cock is turned to on position preparatory to lighting the burner. This operation completes the 65 electric circuit controlling that particular

burner, it being remembered that heat is required at the burner to break the same circuit thermostatically by means of thermal disc 2. Immediately upon turning on the cock heat is generated in heating element 14 70 which in turn expands the thermal medium 29^a forcing toward closed position the valve gate 24 by the enforced compression of expanding and contracting tube 30. If, however, the gas at the burner is ignited before 75 the time interval that exists between the moment the circuit is completed and the valve commences to close and the moment the valve is completely closed, elapses, the heat generated by such ignition of the gas will 80 thermostatically break the circuit at the burner and the valve will not close; the burner, therefore, functioning as intended.

Should the flame become extinguished for 85 any reason whatever other than that of purposely turning off the cock, the thermal disc 2 will automatically complete the circuit again and the valve will shut off the supply of gas. Or should a child, for 90 example, approach an unignited burner and turn the cock to on position, the circuit would be completed and the valve would close. Thus it is seen that unignited gas cannot flow from the burner.

95 I am aware that other devices purporting to accomplish the ends above set forth have been designed and experimented with but none have ever merited extensive usage because of their costly adaptation to standard equipment, because they were not sufficiently automatic, because of bulky size and because they were easily disordered and not at all positive of operation. My invention overcomes each of these obstacles and can be applied at low cost to all gas fixtures in an 100 entire household.

105 As many changes could be made in the above construction and as many apparently widely different embodiments of this invention could be made without departing from the scope thereof, it is intended that all matter contained in the above description or shown in the accompanying drawings shall be interpreted as illustrative and not in a limiting sense.

110 What I claim as new and desire to secure by Letters Patent of the United States is:

1. The combination with a fuel burning fixture having a control cock, a fuel supply conduit to the fixture, and a safety shut-off valve in said conduit, of means, including an electric actuating circuit, for adjusting said valve, and means for opening and closing said circuit to control the adjustment of said valve, said means including a thermally operated snap action switch controlled by flame conditions at the fixture, and another switch controlled by movement of the fixture cock.

115 2. The combination with a fuel burning

- fixture having a control cock, a fuel supply conduit to the fixture, and a safety shut-off valve in said conduit, of means, including an electric actuating circuit, for adjusting said valve, and means for opening and closing said circuit to control the adjustment of said valve, said means including a thermally operated switch in said circuit controlled by flame conditions at the fixture, and another switch controlled by movement of the fixture cock. 65
3. The combination with a fuel burning fixture having a control cock, a fuel supply conduit to the fixture, and a safety shut-off valve in said conduit, of means, including an electric actuating circuit, for adjusting said valve, and means for opening and closing said circuit to control the adjustment of said valve, said means including a thermally operated snap action switch in said circuit controlled by flame conditions at the fixture, and another switch controlled by movement of the fixture cock. 70
4. The combination with a fuel burning fixture having a control cock, and a fuel supply conduit to the fixture, of means for shutting off the supply of fuel to the fixture through said conduit when the cock is in adjustment to pass fuel and the fuel is not burning at the fixture, said means including a thermally operated shut-off valve in said conduit, and an electric heating device for supplying heat to operate said valve. 75
5. The combination with a fuel burning fixture having a control cock, and a fuel supply conduit to the fixture, of means for shutting off the supply of fuel to the fixture through said conduit when the cock is in adjustment to pass fuel and the fuel is not burning at the fixture, said means including a thermally operated shut-off valve in said conduit, an electric heating device for supplying heat to operate said valve, an electric circuit for said heating device, a thermally operated switch controlled by flame conditions at the fixture, and another switch controlled by adjustment of the fixture cock. 80
6. The combination with a fuel burning fixture having a control cock, and a fuel supply conduit to the fixture, of means for shutting off the supply of fuel to the fixture through said conduit when the cock is in adjustment to pass fuel and the fuel is not burning at the fixture, said means including a thermally operated shut-off valve in said conduit, an electric heating device for supplying heat to operate said valve, an electric circuit for said heating device, a thermally operated switch controlled by flame conditions at the fixture, and another switch controlled by adjustment of the fixture cock, said switches being in series in said heating device circuit. 85
7. The combination with a fuel burning fixture having a control cock, and a fuel supply conduit to the fixture, of a thermo-electrically operated valve, including an electric actuating circuit, for shutting off the flow of fuel to said fixture, and means for opening and closing said circuit to control the adjustment of said valve, said means including an electric switch thermally actuated by flame conditions at the burner, and another switch actuated by movement of said fixture cock. 90
8. The combination with a fuel burning fixture having a control cock, and a fuel supply conduit to the fixture, of a thermo-electrically operated valve, including an electric actuating circuit, for shutting off the flow of fuel to said fixture, and means for opening and closing said circuit to control the adjustment of said valve, said means including an electric switch thermally actuated by flame conditions at the burner, and another switch actuated by movement of said fixture cock, said switches being in series relation in said valve actuating circuit. 95
9. The combination with a fuel burning fixture having a control cock, and a fuel supply conduit to the fixture, of a thermo-electrically operated valve, including an electric actuating circuit, for shutting off the flow of fuel to said fixture, two electric switches in series in said circuit, means thermally responsive to flame conditions at the fixture for operating one of said switches, and means responsive to movement of the fixture cock for operating the other of said switches, whereby said valve operating circuit is closed to cause said valve to shut off the supply of fuel to the fixture whenever the fixture cock is in position to allow fuel to pass and there is no corresponding flame at the fixture. 100
10. In a thermostatic control, including a container supplied with material expansible under the influence of heat, and a device adjacent the container for heating the same, a protective housing enclosing said container and heating device, said housing having adjustable vents, whereby the heating of said container by said heating device may be controlled in accordance with the amount of ventilation afforded by the adjustment of said vents. 105
11. In a thermostatic control, including a container supplied with material expansible under the influence of heat, an electric heating coil surrounding the container for heating the same, a protective housing enclosing said container and coil, and adjustable vents in said housing, affording ventilation to said coil and container in accordance with the adjustment of said vents. 110

In testimony whereof I affix my signature.

MARCUS B. MATSON.
